(57) **CLAIM**

The ornamental design for a hook with articulating latch, as shown and described.

DESCRIPTION

FIG. 1 is a perspective rear view of a preferred embodiment of a hook with articulating latch constructed in accordance with the present invention;

FIG. 2 is a perspective front view thereof;

FIG. 3 is a right side view thereof;

FIG. 4 is a left side view thereof;

FIG. 5 is a rear view thereof;

FIG. 6 is a front view thereof;

FIG. 7 is a top view thereof; and,

FIG. 8 is a bottom view thereof.

The broken lines in the drawings depict environmental subject matter/or parts of the hook with articulating latch only and form no part of the claimed design.
